UNITED STATES PATENT OFFICE.

REID J. McCREDIE, OF BUFFALO, NEW YORK.

MOTOR-VEHICLE RADIATOR.

1,333,668.

Specification of Letters Patent. Patented Mar. 16, 1920.

Application filed December 12, 1918. Serial No. 266,460.

To all whom it may concern:

Be it known that I, REID J. McCREDIE, a citizen of the United States, residing at Buffalo, in the county of Erie and State of New York, have invented certain new and useful Improvements in Motor-Vehicle Radiators, of which the following is a specification.

The present invention comprehends generally improvements in that class of inventions known as heat exchanges and more particularly relates to an improved motor vehicle radiator.

It is the primary aim and object of this invention to provide a device of the above mentioned character designed with independent or separate detachable water conducting tubes of novel construction to insure of an effective cooling of the water as it passes through the tubes when passing from the upper to the lower part of the radiator.

More particularly this invention contemplates the provision of a device of the above mentioned character which consists generally of upper and lower tanks connected by side bars and arranged in communication with each other by the improved tubes detachably fastened in position by couplings of improved construction, the component parts of the device being so related that they may be shipped in a collapsed or a knocked-down form and are capable of being readily assembled and easily repaired.

It is a more specific object of this invention to provide a device of the above mentioned character wherein the sides of the tubes are designed with arches arranged alternately with respect to each other while acting in conjunction therewith are the partitions designed to deflect the water into the arch portions of the tube to in consequence insure of a quick cooling of the water as it passes from the upper tank to the lower tank.

Among the other aims and objects of this invention may be recited the provision of a device of the above mentioned character wherein the number of parts are comparatively few, the construction simple, the cost of production low and the efficiency high.

Other objects as well as the characteristic features and scope of this invention will be more readily apparent from the following description taken in connection with the ac-

companying drawings, and pointed out in the claims, forming a part of this specification.

The invention is clearly illustrated in the accompanying drawings, in which:

Figure 1 is a vertical sectional view taken through the radiator,

Fig. 2 is a top plan detail of one of the upper coupling plates showing the flanged end of the tube positioned therein,

Fig. 3 is an enlarged transverse sectional detail of the connection between the tube and the upper tank,

Fig. 4 is an enlarged transverse sectional view taken on line 4-4 of Fig. 3, and

Fig. 5 is a sectional view taken on line 5-5 of Fig. 3.

Similar characters of reference are employed in all of the above described views to indicate corresponding parts.

Referring now, more particularly, to the accompanying drawings there is provided the improved radiator which preferably consists generally of an upper tank indicated in its entirety by the numeral 1, a lower tank generally designated 2 and held in spaced relation with each other by means of the side bars 3 and arranged in communication with each other through the instrumentality of the improved tube generally designated by the numeral 4.

The upper tank has its rear wall 5 detachably connected with the top and bottom walls by means of the lock seams 6 and 90 when detached permits of the making of repairs. In addition, this wall 5 is fitted with a nipple 7 adapted to receive an inlet pipe (not shown) while the top wall is formed with an opening 8 to facilitate filling of the radiator and about this opening is formed an upright collar 9 detachably closed by means of a cap 10.

The lower tank 2 has its inner and bottom walls formed integral with each other 10 and arranged in connection respectively with the front and top walls by means of lock seams 11 which when disengaged permit of access to the lower tank. In addition, the rear and bottom walls of the lower tank are fitted with a nipple 12 adapted to receive an outlet pipe (not shown).

The opposite faces of the tanks are formed with series of opposed openings 13 while integral with the upper face of the bottom wall of the upper tank about the openings therein are upright collars 14.

Likewise, depending from the lower faces of the top wall of the bottom tank and about the openings in the top wall are other collars 15.

- 5 Each of the tubes 4 are of rectangular configuration in cross section the upper and lower edges of the tubes being formed with outwardly extending flanges 16. Coupling plates 17 are now employed and are formed 10 with longitudinal slots to accommodate the adjacent end portions of the tubes while the adjacent faces of the plates are provided with recesses or countersinks 18 to accommodate the flanges 16 so that the outer faces 15 of the flanges lie flush with the adjacent faces of the coupling plates. Packing elements or washers 20 are positioned between the walls of the tank and the adjacent flanges and coupling plates to effect water-tight 20 joints at the ends of the tubes while the outer projecting portions of the connecting plates are formed with openings 21 through which are passed suitable fasteners such as screws 22, the threaded shanks of which are 25 anchored in the reinforcing bars 23 positioned on the inner faces of the tanks as indicated in Fig. 1. The heads of the screws are formed with notches 24 on their inner faces and when tightened embrace lugs 25 30 on the adjacent faces of the coupling plates, such arrangement serving to prevent accidental movement of the screws when the radiator is subject to vibration during the operation of the engine of the motor vehicle (not shown). Protecting covers 26 are 35 arranged over the reinforcing and bracing bars 23, the engagement between the covers and the bars being frictional to permit of the removal of the covers when it is desired to 40 make repairs or place the radiator in a knocked-down form.

In insuring of the effective cooling of the hot water as it passes through the tubes from the upper tank to the lower tank, the opposed side walls of each of the tubes are 45 formed with suitably spaced outwardly extending arched portions 28 alternately arranged with respect to each other. A vertical partition generally designated by the 50 numeral 29 is arranged through each of the tubes and in spaced relation to the opposed side walls and in effect is constructed in a zig-zag form in vertical cross section, each of the inclined portions 30 terminating opposite and medially of the arched portions while the metal from which each of the partitions is formed is folded upon itself at 55 the juncture of the inclined portions to provide outwardly extending deflecting lips or 60 baffles 31. The baffles are arranged to project alternately from opposite sides of the partition and extend partially within the adjacent arched portions 28 to insure of the 65 water which passes down each of the tubes passing into the adjacent arched portion so

as to become cold when it reaches or enters the bottom or lower tank 2. These partitions 29 are clamped in the seams A formed in the tubes 28 as shown in Fig. 5 of the drawing, the opposite edges of the partitions 70 29 being straight so that the same will engage in the seams and thereby make a fluid tight joint therebetween, while the zig-zag form in vertical cross section with the baffles 75 31 are made by bending the plate between the straight edges thereof.

In connecting the side bars 3 which are preferably of a channeled form in cross section to the adjacent tanks 1 and 2 it is preferred that angle brackets 32 be employed, 80 the portions thereof being formed with openings through which are passed nut and bolt arrangements 33 for respectively engaging the side bars and the reinforcing bars 23, thereby increasing the rigidity of the 85 radiator in its entirety when assembled.

It is believed in view of the foregoing description that a further detailed description of the operation of the invention is entirely unnecessary. Likewise, it is believed that 90 the advantages of the invention will be readily apparent.

Still further embodiments of the invention than those herein especially defined may be resorted to as conditions or preference may 95 dictate, as may be in keeping with the here-to appended claims.

Having thus fully described the invention what is claimed as new and desired to be secured by Letters Patent, is: 100

1. A radiator including spaced upper and lower tanks, a plurality of spaced tubes connected to the tanks for establishing communication between the tanks, the opposite walls of each of the tubes being formed 105 with arched portions positioned alternately with respect to each other, a partition in each tube, and deflecting lips projecting from the opposite faces of the partitions and extending slightly within the adjacent 110 arched portions.

2. A radiator including spaced upper and lower tanks, a plurality of spaced tubes connected to the tanks, the opposite walls of the tubes being provided with spaced 115 arched portions positioned alternately with respect to each other, a vertical partition arranged in each tube and spaced slightly from the opposed side walls of the tube, said partition being of zig-zag shape in vertical 120 cross section and having the oppositely inclined portions inclined toward the adjacent arched portions, outwardly projecting deflecting lips extending from the points of juncture of the adjacent inclined portions of 125 the partitions and extending slightly within the adjacent arched portions.

3. In a radiator, the combination with spaced upper and lower tanks having openings in their adjacent walls and tubes ar- 130

- ranged between the tanks in alinement with the opposed openings, of coupling plates provided with slots for accommodating the adjacent ends of the tubes and having their 5 inner faces provided with countersinks about the slots, outwardly extending flanges projecting from the ends of the tubes and accommodated in the countersinks, washers positioned between the tanks and the adjacent 10 plates and flanges, reinforcing bars arranged on the inner faces of the walls of the tanks having openings therein and fastening devices passed through the plates and the washers and adjacent walls of the tanks and anchored in the reinforcing bars for detachably and independently connecting the tubes to the tanks and providing watertight joints therebetween. 15

In testimony whereof I affix my signature hereto.

REID J. McCREDIE.
